WIDE INLET ROTARY PUMP FOR CIRCULATING LIQUIDS UNDER VACUUM

Edmond S. Perry, Rochester, N. Y., assignor, by
mesne assignments, to Eastman Kodak Company,
Rochester, N. Y., a corporation of New Jersey

Application October 14, 1946, Serial No. 703,208

3 Claims. (Cl. 103—126)

1

This invention relates to an improved device for circulating liquids in evacuated apparatus.

The practice of circulating liquids in evacuated apparatus by means of conventional pumps is limited by vapor locking of the conduits leading to the inlet ports of the pump. These conduits are usually pipe or tube of small diameter. Gravitational flow of liquid through them is impeded by liberated gases which, because of their continual expansion, become lodged in the conduits.

This invention has for its object to provide an improved pump for circulating liquids under vacuum such as in a high-vacuum unobstructed-path still. Another object is to provide a pump not subject to vapor lock. A still further object is to provide a wide inlet rotary pump the operation of which will not be impeded by the formation of bubbles. Another object is to improve the state of the art. Other objects will appear hereinafter.

These and other objects are accomplished by my invention which includes a rotary type pump with a wide inlet effected by eliminating the inlet pipe and restricting the size of the head plate to expose the gears at the pump inlet. A pump of this design located, for example, at the bottom of a liquid drain reservoir in a high-vacuum unobstructed-path still may be used to circulate the liquid to another part of the still.

In the following description wherein like numbers refer to like parts I have set forth several of the preferred embodiments of my invention but it is to be understood that these are given by way of illustration and not in limitation thereof. In the accompanying drawings wherein I have illustrated two embodiments of my invention, Figure 1 is a side-by-side rotary gear pump with the head plate removed, Figure 2 is a gear-within-gear rotary pump with the head plate removed, and Figure 3 is a 90° rotated section showing the pump attached to a reservoir containing liquid to be pumped. Figure 3 illustrates the operation of the gear-within-gear rotary pump of Figure 2.

Referring to the drawings, numeral 10 designates the inlet of the pump. This is similar to a conventional pump except that the inlet conduit has been eliminated and a portion of the pump housing cut away so as to expose the gears. Numeral 11 designates the pump outlet. Numeral 12 designates an impeller on the side-by-side type rotary pump. Numeral 13 designates the rotor gear of the gear-within-gear rotary pump and numeral 14 designates the idler or

2

stator gear. Numeral 15 designates the pump housing. Numeral 16 designates the pump head plate or cover. Numeral 17 designates the shaft which rotates the pump. Numeral 18 designates the pump bearing. Numeral 19 designates the base plate of a liquid reservoir. Numeral 20 designates an opening in the base plate to which the pump is connected.

In operation a pump of the type described is placed below the surface of any liquid which it is desired to circulate in the vacuum chamber. The pump inlet 10 is comparatively wide and includes a portion of the gears. Any gas bubbles which form around the inlet can easily rise to the surface of the liquid and escape. By omitting the inlet conduit and cutting away a portion of head plate 16 around the inlet I have eliminated all possibility of vapor lock and produced a pump which is positive operating. The exhaust portion of the gears is covered by the plate, thus forcing the circulating liquid out through tube 11. Housing 15 is mounted to base plate 19 of a reservoir so that opening 20 in this plate coincides with that in head plate 16. The gears are then in direct contact with the bulk of the liquid.

The inlet may be as large as possible provided there is no interference with the action of the outlet port. It is only necessary to maintain some bearing surface between the inlet port and outlet port to insure pumping action. Dotted lines have been inserted in Figures 1 and 2 to illustrate the bearing surface required. If the head plate covers the entire gear area except the crescent-shaped portion indicated by the dotted line around inlet port 10 there will still be a sufficient inlet area to prevent vapor locking. On the other hand if the head plate covers only the crescent-shaped portion of the gear area indicated by the dotted line around outlet port 11 there will still be sufficient bearing area to allow the pump to function, and the possibility of vapor locking is reduced to a minimum. The exposed gear area may be restricted to the small area indicated by the dotted line crescent around inlet port 10 or it may be large enough to include all the gear area except that covered by the dotted line crescent around outlet port 11.

It is obvious that many variations may be made in the size of the inlet opening. The size required depends upon the type of fluid being handled, the degree of vacuum, and the temperature. More volatile fluids, higher vacuums, and higher temperatures all go to increase the size of the opening required. Inlet size can be designed to fit operating requirements. For rela-

tively non-volatile liquids, leaving about 15% of the head plate area open around the pump inlet will give a pump having satisfactory performance characteristics. For more volatile liquids as much as 75% of the head plate area may be left open. If 25% of head plate area in the vicinity of the outlet is covered there will be sufficient bearing surface to enable the pump to operate.

What I claim is:

1. In a system for handling liquid material under high vacuum conditions, the combination with an evacuable chamber adapted to contain liquid material, of a gear pump assembly comprising intermeshing rotatable gear means, a housing enclosing one lateral face and the peripheral extent of said gear means, an outlet port in said housing adjacent the periphery of said gear means, and head plate means enclosing not less than 25% and not more than 85% of the other lateral face opposite to said one lateral face of said gear means in a zone adjacent said outlet port, said chamber being arranged to cause liquid material to flow by gravity from said chamber to said pump assembly and having an outlet opening in a lower portion of said chamber of cross-sectional area not less than area of the unenclosed portion of said other lateral face of said gear means, and generally unconstricted means providing direct communication between said outlet opening of said chamber and said unenclosed portion of said other lateral face of said gear means, said generally unconstricted means having a cross-sectional area not substantially smaller than said outlet opening in said chamber.

2. In a system for handling liquid material under high vacuum conditions, the combination with an evacuable chamber adapted to contain liquid material, of a gear pump assembly comprising intermeshing rotatable gear means, a housing enclosing one lateral face and the peripheral extent of said gear means, an outlet port in said housing adjacent the periphery of said gear means, and head plate means enclosing not less than 25% and not more than 85% of the other lateral face opposite to said one lateral face of said gear means in a zone adjacent said outlet port, said chamber having an outlet opening in a lower portion thereof of substantially the same cross-sectional area as the unenclosed portion of said other lateral face of said gear means, said housing being secured to said chamber in liquid-tight relation with said outlet opening in said chamber coinciding

5 with said unenclosed portion of said other lateral face providing direct communication between said chamber and said gear means.

3. In a system for handling liquid material under high vacuum conditions, the combination with an evacuable chamber adapted to contain liquid material, of a gear pump assembly positioned immediately below said chamber and comprising generally horizontally disposed intermeshing rotatable gear means, a housing enclosing the lower lateral face and the peripheral extent of said gear means, an outlet port in said housing adjacent the periphery of said gear means, a head plate enclosing not less than 25% and not more than 85% of the upper lateral face of said gear means in a zone adjacent said outlet port, said chamber having an outlet opening in the bottom thereof of cross-sectional area substantially equal to the area of the unenclosed portion of said upper lateral face, said housing being secured to said chamber in liquid-tight relation with said outlet opening in said chamber directly above and generally coinciding with said unenclosed portion of said lateral face and thereby providing direct communication between said chamber and said pump assembly.

Certificate of Correction

Patent No. 2,499,158

February 28, 1950

EDMOND S. PERRY

It is hereby certified that errors appear in the printed specification of the above numbered patent requiring correction as follows:

Column 1, line 55, for the word "designate" read *designates*; column 3, line 27, for "areea" read *area*; line 28, for "than area" read *than the area*; same line, for "unclosed" read *unenclosed*;

and that the said Letters Patent should be read with these corrections therein that the same may conform to the record of the case in the Patent Office.

Signed and sealed this 20th day of June, A. D. 1950.

[SEAL]

THOMAS F. MURPHY,
Assistant Commissioner of Patents.
